UNITED STATES PATENT OFFICE.

HENRY PRICE BALL, OF NEW YORK, N. Y., ASSIGNOR TO GENERAL ELECTRIC COMPANY, A CORPORATION OF NEW YORK.

OIL-SWITCH.

1,113,087.

Specification of Letters Patent.

Patented Oct. 6, 1914.

Application filed October 11, 1905, Serial No. 282,233. Renewed April 8, 1914. Serial No. 830,536.

To all whom it may concern:

Be it known that I, HENRY PRICE BALL, a citizen of the United States, residing at New York, county of New York, State of New York, have invented certain new and useful Improvements in Oil-Switches, of which the following is a specification.

The present invention relates in general to electric switches and more particularly to 10 that class, designed for handling currents of large amperage and high potential, in which the pressure produced by the arc is confined and directed so as to assist in breaking the circuit.

15 In carrying out my invention I utilize the pressure produced by the arc drawn at one of a plurality of break points to extinguish the arcs drawn at the other break points. In a polyphase circuit this is readily accomplished by breaking all the legs of the circuit simultaneously within a single inclosure, or a plurality of intercommunicating inclosures, and relying on the inequality of pressures produced by the different arcs to 25 rupture the different legs of the circuit. In such a circuit the energy in each leg will vary from instant to instant and the phases will differ in the different legs so that upon the simultaneous breaking of all the legs of 30 the circuit the arcs drawn will correspondingly vary in energy values and the arc having the least energy will be first extinguished, and then the next vigorous arc, and so on, until all the arcs are extinguished, in each 35 case the inclosed insulating medium whether oil or air being forced by the arc of greatest energy against the arc of least energy. Furthermore, if desired, each leg of the circuit may be provided with two break points in 40 series arranged to draw their arcs in sequence. With this arrangement the arc first drawn will force the oil against the arc last drawn as well as against the weaker arcs in 45 the other legs of the circuits.

45 The present invention comprises means for rupturing a circuit in the manner above indicated, together with certain details and structural features, all of which will be more fully understood upon reference to the 50 following detailed description taken in connection with the accompanying drawing, in which—

Figure 1 is a side elevation of a standard type of switch constructed in accordance 55 with the present invention; Fig. 2 is a dia-

gram illustrating especially the manner of establishing communication between the different oil pots of such switch; and Fig. 3 is a detailed view of a modified form of switch in which the arc is drawn in one inclosure 60 prior to the other.

Throughout these figures like characters refer to like parts.

In the switch shown, which is of a common and well-known type, 10 designates the 65 oil pots or chambers within which the arcs are drawn by the separation of the fixed and movable contacts 11 and 12. These pots, of which there are two per phase, are located within fire-proof cells formed by brick walls 70 13 built upon a suitable base 14 of insulating material and provided with an insulating cap 15 of slate or other refractory non-conducting material. For the purpose of inspection and access to its interior, the cell is 75 provided with suitable doors 16 having latches 17 for holding them closed. The fixed switch contacts 11 are carried by partitions 18 of suitable conducting material located some distance from the bottoms of 80 the pots and in electrical engagement with them. Each pot is electrically connected to and mechanically supported by a terminal 19 which extends through a suitable insulating base 20 carried within the cell. The circuit is completed between the contacts 11 by 85 means of the contact rods 12 which are electrically and mechanically connected by the yoke 21, secured at its center to the lower end of a reciprocating rod 22 made of wood 90 or other insulating material, which is adapted to be actuated by the operating mechanism located upon the top of the cell. As the rod 22 is reciprocated the contact rods 12 are moved through the insulating guides 23 located in the top of the oil pots into and out of engagement with their coöperating contacts 11.

In accordance with the present invention the oil pots 10, of each leg of the circuit, are 100 connected by a pipe 24 located near their lower ends for the purpose of establishing communication to permit the free passage of the oil or other insulating fluid, whose level is indicated at 24^a. The pots of each 105 leg of the circuit are also connected, as clearly illustrated in Fig. 2, by similar connecting pipes 25.

In the operation of the switch shown, which is intended for a three-phase circuit, 110

the contact rods 12 of all three phases are simultaneously drawn out of engagement with their coöperating fixed contacts 11 and an arc is drawn in each one of the oil pots 5 having an energy value corresponding to the value of the current in the particular leg of the circuit at the instant of rupture. The resulting inequalities of pressure in the oil pots of the different phases will tend to 10 equalize thus causing a flow of oil from the pots in which the arcs are the most vigorous to the remaining pots. This flow will create a stronger current of oil up through the fixed contacts 11 of said remaining pots 15 which will greatly assist in rupturing the arcs drawn at those particular contacts. With the arcs in one leg of the circuit ruptured there will be a flow of oil between the oil pots of the other phases and a like rupture of the weaker arc which will completely 20 rupture the entire circuit.

Referring to the modification illustrated in Fig. 3 the construction is the same as that heretofore described except that one of the 25 movable contact rods 12^a is shorter than the companion rod 12^b. Due to this construction two breaks take place in each leg of the circuit and in addition to the equalization of pressures between the oil pots of the 30 different phases a flow of oil is produced between the pots of the same phase since the arc is drawn by the contact rod 12^a prior to the contact rod 12^b.

In order to prevent the rupture of the oil 35 pots in case of excessive pressure they may be provided with a safety valve such as is shown in one of the pots in Fig. 3. This valve is formed by a spring-pressed plate 26 closing an aperture 27 in a partition 28 located above the fixed contact and the surface 40 of the oil. In case of excessive pressure the air or gases may escape through this aperture into the chamber above the partition 28 and thence by the way of one or more vents 45 28^a to atmosphere. Obviously the modified construction of Fig. 3 may also be employed for the purpose of rupturing a single phase alternating current circuit or a direct current circuit as well as a polyphase circuit. 50 As shown in Fig. 1, the partition 28 and safety-valve 26 may be omitted, in which case the vents 28^a are made of restricted area, so as to prevent the free escape of the gases generated in the oil-pots 10 when the 55 arc is formed. Under normal conditions the gases escape slowly, whereby sufficient pressure is retained upon the oil to extinguish the arcs; but in case of excessive pressure, these restricted openings permit the 60 gases to escape rapidly enough to prevent injury to the oil-pots.

For the purpose of illustrating a completely operative device I have shown a standard type of operating mechanism by 65 which the reciprocating rods 22 which carry

the bridging contacts are given their reciprocating motion. This mechanism comprises rock arm 29 to the outer end of which the rod 22 is secured and which is pivotally secured at its other end to the upper end of 70 the rock arm 30. The outer end of the rock arm 29 is adapted to move in a vertical right line and the power for producing this movement is obtained from a rock shaft 31 provided with a crank 32. The right-line 75 movement of the outer end of the rock arm 29 is obtained by means of a system of links which constitute a parallel motion mechanism. This system comprises a link 33 which is connected at its center by a link 34 80 to a fixed point 35. This same central point is connected to the crank 32 by connecting rod 36 and to a point 37 on the rock arm 29 by a link 38. The length of the link 34, one-half the length of the link 33 and the 85 distance between the points 37 and 39 are equal. The length of the links 38 are also equal to the distance between the points 39 and 40. With this construction the outer 90 ends of the arms 29 and 33 move in vertical right lines, the latter between the coiled actuating springs 41 and 42. From this construction it will be seen that when the crank 32 lies in its substantially vertical positions the springs 41 and 42 will be compressed by 95 the outer end of the link 33. Obviously then if the shaft 31 be rotated so as to compress either one of these springs and is held in this position the switch will be either in open or closed position and the appropriate 100 spring will be compressed and ready to throw the switch to the opposite position whenever the shaft 31 is released. For the purpose of holding the shaft in these positions stops 43 are provided on a gear wheel 105 44. These stops rotate with the shaft and are adapted to be engaged by the stop 45 pivoted at the point 46 and normally held in engaging position by toggle 47. The toggle 47 may be broken in any desired way to 110 rock the stop 45 so as to free the appropriate stop 43 and allow the actuating spring to throw the switch. In the present instance plunger 48 is employed for this purpose. It is located directly beneath the center of the 115 toggle 47 and is actuated by means of a magnet coil located within the casing 49. The switch may be set by rotating the shaft 31 either by hand or otherwise. In the present instance I have shown an electric motor 50 120 which is geared through a suitable train of gearing to the shaft 31 for this purpose. In this train of gearing is a magnetic clutch 51 which may be cut in or out to stop the rotation of the shaft 31 at the appropriate point. 125

Obviously certain changes and alterations may be made in the construction and organizations presented in this application without departing from the spirit and scope of my present invention; I therefore do not 130

wish to be unduly limited but aim to cover by the terms of the appended claims all such alterations and modifications.

What I claim as new and desire to secure 5 by Letters Patent of the United States, is,

1. An electric switch, comprising a plurality of pairs of separable contacts, a closed chamber containing insulating fluid for each pair, and means for transmitting 10 pressure developed in one chamber to the insulating fluid in the other chambers, and thereby directing the fluid therein against the arc to extinguish it.

2. An electric switch, comprising a plurality of pairs of separable contacts, a closed chamber for each pair, and means for directing any excess of pressure produced by the drawing of an arc in one chamber against the arc drawn in another so 20 as to assist in its extinguishment.

3. The combination with a polyphase circuit, of an electric switch comprising a break point in each leg of said circuit, and means for confining the pressure produced 25 by the arc drawn at the break point in one leg and directing it against an arc drawn at the break point in another leg so as to assist in its extinguishment.

4. An electric switch, comprising a plurality of coöperating separable contacts arranged to form a plurality of break points and to break in succession at said points, a closed chamber for inclosing the contacts at each break point, and communicating 35 passages between said chambers.

5. An electric switch, comprising a plurality of oil pots, an oil-communicating passage between said pots, fixed contacts within said pots, and a bridging contact arranged 40 to disengage one of said contacts prior to the other.

6. An electric switch, comprising a plurality of oil pots, an oil-communicating passage between said pots, fixed contacts within 45 said pots, a bridging contact arranged to disengage one of said contacts prior to the other, and a safety valve for controlling the pressure in the oil pot where the contacts first separate.

50 7. An electric switch comprising separable contacts, a chamber for said contacts having an opening in the wall thereof through which one of said contacts extends, the diameter of the opening being greater 55 than that of the contact, and a safety valve movable independently of said contact for closing said opening.

8. A double break oil switch comprising two pairs of separable coöperating contacts, 60 means containing oil surrounding said contacts, said means comprising a chamber inclosing each pair of contacts and a pressure equalizing conduit joining said chambers and permitting a circulation of the oil.

65 9. An electric switch comprising a ves-

sel containing insulating fluid, coöperating fixed and movable contacts mounted to separate in said vessel in said insulating fluid, a partition in said vessel provided with a vent to permit fluid put under pressure by the arc formed upon the separation of said contacts to flow from one part of the vessel to another, said movable contact being mounted to move through said vent, and a member through which said movable contact passes with slight clearance, said member being mounted adjacent said partition with its surface at an angle to the axis of said vent to form a deflector for the fluid put under pressure by the arc.

70 10. An electric switch comprising a vessel containing insulating fluid, a partition mounted in said vessel and provided with a vent, coöperating fixed and movable contacts mounted to separate in said vessel beneath said partition, and a spring pressed plate through which said movable contact passes with slight clearance mounted to normally obstruct the flow of fluid through 75 said vent from beneath the partition and to yield in response to pressure of fluid beneath said partition to permit fluid to flow from beneath said partition to the upper surface thereof.

80 11. An electric switch comprising a vessel containing insulating fluid, a partition mounted in said vessel to divide said vessel into two compartments, said partition being provided with a vent to permit fluid to flow from one compartment into the other, 85 relatively movable coöperating contacts mounted to separate in one of said compartments, one of said contacts being movable out of said compartment through said vent, a member surrounding said contact 90 with slight clearance, and yieldingly mounted to coöperate with said partition to normally close said vent, said means being actuated by pressure in one compartment to form with said vent a restricted outlet to 95 the other compartment.

100 12. An electric switch comprising a chamber containing insulating fluid, and having in one wall thereof a vent to permit escape of said fluid under pressure, a fixed contact 115 mounted in said chamber, a movable contact smaller than said vent movable into and out of said chamber through said vent to coöperate with the fixed contact in said chamber, and a spring pressed closure 120 mounted to coöperate with said movable contact and said partition to normally prevent escape of fluid from said chamber, while said movable contact is in said chamber, said closure being lifted by pressure in 125 said chamber.

13. An electric switch comprising a chamber containing insulating fluid and having in one wall thereof a vent to permit escape of said fluid under pressure, a fixed 130

1. contact mounted in said chamber, a movable contact smaller than said vent movable into and out of said chamber through said vent to coöperate with the fixed contact in 5 said chamber, a valve disk larger than said vent slidably mounted on said movable contact to make a substantially fluid tight fit with the walls of said vent and with said contact when in normal position, and means 10 for yieldingly holding said valve disk in normal position against the pressure of the fluid in said chamber.

14. An electric switch comprising a chamber containing insulating fluid, and having 15 in one wall thereof a vent to permit escape of said fluid under pressure, a fixed contact mounted in said chamber, a movable contact smaller than said vent movable into and out of said chamber through said vent to coöperate with the fixed contact in said chamber, and a closure for said vent yieldingly held in position to close said vent, said closure having an opening through which 20

said movable contact passes to enter and leave said chamber.

15. A circuit interrupting device comprising a pressure retaining chamber containing oil and having a vent in one wall thereof, a stationary contact in said chamber, a movable contact mounted to separate 30 from said stationary contact and thereby draw an arc in said chamber and to move out of said chamber through said vent, and a fluid intercepting member through which said movable contact passes with slight 35 clearance, said member being mounted adjacent said vent to intercept and deflect away from the path of the movable contact the greater portion of the jet of fluid discharged from said vent.

In witness whereof, I have hereunto set my hand this sixth day of October, 1905.

HENRY PRICE BALL.
